UNITED STATES PATENT OFFICE.

LUTHER CALVIN REED, OF DALLAS, TEXAS.

DRIER.

1,276,957.

Specification of Letters Patent. Patented Aug. 27, 1918.

Application filed February 21, 1918. Serial No. 218,545.

To all whom it may concern:

Be it known that I, LUTHER CALVIN REED, a citizen of the United States, residing at Dallas, in the county of Dallas and State 5 of Texas, have invented certain new and useful Improvements in Driers, of which the following is a specification.

This invention relates to driers and has for its object the provision of an apparatus 10 which may be installed at a low cost and will prove efficient in operation. The mechanism is intended primarily for use in drying fertilizers, animal hair, and similar products but is adapted for drying vegetable 15 tables and other commodities.

The invention is illustrated in the accompanying drawings in which—

Figure 1 is a side elevation, partly broken-away, of an apparatus embodying my improvements;

Figs. 2 and 3 are elevations looking at the opposite ends of the apparatus;

Fig. 4 is an enlarged vertical section on the line 4—4 of Fig. 1;

Fig. 5 is a detail transverse section through one of the drying units and more or less diagrammatic in character;

Fig. 6 is an enlarged longitudinal section on the line 6—6 of Fig. 2;

Fig. 7 is a detail section taken on the line 7—7 of Fig. 6;

Figs. 8 and 9 are, respectively, a side elevation and a plan view of an elbow forming a part of the vent.

In carrying out my invention, I employ a plurality of steam jackets or pipes in which are mounted spiral conveyers, the conveyers in the alternate pipes being rotated in opposite directions so that the material will be caused to travel back and forth through the successive units.

The invention also comprehends the provision of simple and compact means for operating the spiral conveyers and also includes means for venting the apparatus or drawing-off the foul air and obnoxious odors. In the accompanying drawings the reference numeral 1 indicates a base of any substantial character upon which are erected brackets 2 at the ends thereof and in the said brackets are secured steam jackets or pipes 3 which may be provided in any desired number and are disposed in parallel relation one above another and spaced slightly apart, as clearly shown in Fig. 1. The pipes will preferably be covered with asbestos or

some similar non-heat conducting material, as shown at 4, so that the heat will be retained within the steam pipes or jackets and raise the temperature of the inner tubes 5 within which the spiral conveyers 6 operate. The brackets 2 are provided with lateral perforated lugs or ears 7 so that suitable securing bolts may be inserted therethrough to firmly secure together the superposed brackets, and each bracket is preferably in the form of an annulus having an internal flange or rim 8 adapted to provide a bearing for the pipe or tube 5 and also close the end of the steam pipe 3. The steam pipe may be threaded into the bracket 2, as shown clearly in Fig. 6, and the heat resistant cover 4 will be carried, of course, up to and against the inner face of the bracket. Packing 9 will be preferably provided around the pipe 75 or tube 5 and against the outer face of the flange 8 of the bracket and a gland 10 will be secured upon the rim 11 provided upon the outer face of the bracket so as to compress the packing 9 against the outer peripheral surface of the pipe 5 and thereby prevent leakage and loss of steam or other heating medium. The pipes 5 extend through and beyond the brackets, and means are provided at the ends of said pipes for supporting and driving the conveyers 6 while hoppers and vents are also provided at the ends of the pipes 5 to carry off the obnoxious odors and also permit the passage of the material from one conveyor to the next conveyor, all of which will be presently more fully set forth. To supply the steam or other heating medium to the steam jackets 3 I provide a feed pipe 11' which may lead directly from a steam boiler and extends the full height of the apparatus, being provided at intervals with the branch pipes 12 corresponding in number to the units of the drier and each branch leading into one steam jacket as shown most clearly in Fig. 5. As shown in said Fig. 5, the branch pipe 12 communicates with the steam jacket above the center thereof and at the opposite side of the said jacket and below the center of the same, a return branch 13 leads to an escape or return pipe 14 by which the water of condensation is carried to the boiler to be again converted into steam.

As previously stated, each pipe 5 contains a spiral conveyor 6 and these conveyers are rotated in opposite directions. The shaft 15 of each conveyor is extended through the

ends of the respective pipe 5 and caps 16 which constitute closures for the said ends and are also carried beyond the said caps and, at one end of the apparatus equipped 5 with sprocket wheels 17, a sprocket chain 18 passing around the said sprocket wheels 17 and also around an idler 19 which is supported in brackets 20 extending laterally from some of the caps 16 at an intermediate 10 point of the height of the apparatus, this idler serving to support the intermediate portion of the return run of the sprocket chain so that it will not interfere with the proper rotation of the sprockets 17 and also 15 being adapted for use as a chain tightener to preserve the proper tension upon the chain and compensate for wear of its parts. As clearly shown in Fig. 2, the chain passes around the alternate sprockets at opposite 20 sides thereof so that each sprocket will rotate in an opposite direction to the sprockets respectively above and below it and, consequently, the alternate conveyers will be rotated in opposite directions and therefore 25 feed the material being dried alternately toward the opposite ends of the apparatus. Lubricating cups 21 are provided upon the several caps 16 to lubricate the several conveyers shafts, and in order to impart the 30 necessary rotation to the several parts one, preferably the lowermost, conveyor shaft is equipped with a worm gear 22 which meshes with a worm 23 upon a driving shaft 24 so that motion may be transmitted to 35 the several conveyor shafts from any convenient motor. The shaft 24 and worm 23 are housed within a casing 25 formed upon the outer side of the cap 16 so that the driving gearing will be completely inclosed 40 and may be caused to run in oil if so desired.

The material is fed into the uppermost drier pipe 5 through a hopper 26 at one end thereof which hopper may be of any preferred form and opens directly into the said pipe. The material will pass through the 45 said hopper directly into the interior of the drier pipe and will be at once engaged by the conveyor 6 therein so as to be forced to move slowly through the pipe to the opposite end thereof where it will be deposited in a hopper or chute 27 which leads from the lower side of the said uppermost drier pipe into the upper side of the next sub- 50 jacent drier pipe, as will be readily understood and as shown in Fig. 1. The material will then be at once engaged by the conveyor in the said second drier pipe and will be caused to travel slowly through the 55 same toward the feeding end of the apparatus where it will drop through a second chute 27 into the third drier pipe, and this operation is repeated until the material reaches the discharge end of the lowermost 60 drier pipe whence it passes into an outlet 65

pipe 28 which may lead to any desired point of discharge. The several chutes 27 are tapered somewhat downwardly so as to counteract the tendency of the material to spread and direct the entire body of the 70 same onto the subjacent conveyer. Vent elbows 29 are provided at the ends of the apparatus and these elbows rise from the upper sides of those drier pipes which have the chutes 27 extending from their lower 75 sides, the elbows extending laterally between the adjacent drier units and communicating directly with the vent pipes 30 which rise to points above the uppermost drier unit where they communicate with a 80 common exhaust pipe 31 which leads into a fan or blower 32 from which the outlet pipe 33 extends to any desired point outside the building. The fan or blower 32 may be obviously driven from the driving 85 shaft 24 or connected with the motor independently of said driving shaft and it will also be readily understood that the provision of this venting mechanism prevents the circulation of dust and the deposit of the 90 same upon the apparatus so as to clog its operation, and also carries off from the building the obnoxious odors which are sometimes attendant upon the use of such an apparatus so that the materials being fed 95 into the drier may be inspected thoroughly without any disagreeable features.

My improved drier may be readily installed at any point inasmuch as most of the parts are simply pipes of standard 100 diameters which may be easily obtained in any section of the country and the castings are of such simple construction that they may be easily produced in any well equipped foundry. The parts are very compactly 105 arranged so that a drier of large capacity may be built in a comparatively small space and the operation of the mechanism is free of complications so that a highly skilled attendant is not necessary. Moreover, the 110 simplicity of the construction and arrangement of its parts prolongs the life of the mechanism and permits the machine to be built in less time and at less expense than other machines for the same purpose now 115 known to me. The simplicity of the mechanism also permits it to be efficiently driven with a motor of less horse power than is now required for other machines having the same general object. The heat 120 may be regulated as may be required and the material will be driven through the machine at a low speed so that the production of ammonia will be conserved and this valuable element of fertilizers will not be 125 set free by overheating. As the machine is composed essentially of a plurality of similar units it may be increased in capacity as occasion may demand very readily, and if any one unit should become broken 13

or damaged so as to lose its utility a new unit may be substituted therefor without requiring the provision of an entire new apparatus.

- 5 The embodiment of the invention illustrated is that which I now believe to be the best manner of applying my improvements, but it is to be understood that various changes may be made in the details of construction without departing from the spirit or scope of the invention as the same is defined in the following claims.

Having thus described the invention, what is claimed as new is:

- 15 1. An apparatus for the purpose set forth comprising a plurality of superposed brackets, heating jackets having their ends secured in and closed by said brackets, pipes extending through said jackets and said brackets, caps closing the ends of the pipes, chutes connecting the opposite ends of alternate pipes with the adjacent ends of subjacent pipes between the brackets and the caps, conveyers disposed within the pipes and journaled in said caps, and means for driving the alternate conveyers in opposite directions.
- 20 2. An apparatus for the purpose set forth comprising a plurality of superposed brackets, heating jackets having their ends secured in and closed by said brackets, pipes extending through said jackets and said brackets, caps closing the ends of the pipes, chutes connecting the opposite ends of alternate pipes with the adjacent ends of subjacent pipes between the brackets and the caps, conveyers disposed within the pipes and journaled in said caps, and means for driving the alternate conveyers in opposite directions.
- 25 30 35 40

having branches leading into the respective jackets above the centers thereof, and a return pipe disposed at the opposite side of the apparatus and having branches leading 45 from the respective jackets below the centers thereof.

3. An apparatus for the purpose set forth comprising a plurality of superposed brackets, heating jackets having their ends secured in and closed by said brackets, pipes extending through said jackets and said brackets, caps closing the ends of the pipes, chutes connecting the opposite ends of alternate pipes with the adjacent ends of subjacent pipes between the brackets and the caps, conveyers disposed within the pipes and journaled in said caps, means for driving the alternate conveyers in opposite directions, lateral vents leading from the ends 60 of alternate pipes over the chutes depending therefrom, and an escape pipe common to all the vents.

4. An apparatus for the purpose set forth comprising a plurality of superposed brackets, heating jackets having their ends secured in and closed by said brackets, caps closing the ends of the pipes, chutes connecting the opposite ends of alternate pipes with the adjacent ends of subjacent pipes between 70 the brackets and the caps, conveyers disposed within the pipes and having their shafts journaled in said caps, gears on the ends of the shafts to rotate in opposite directions, a housing on one of the caps around 75 the conveyer shaft extending therethrough, a gear on said shaft within said housing, a driving shaft journaled in said housing, and a worm on the driving shaft within the housing meshing with said gear.

In testimony whereof I affix my signature.
LUTHER CALVIN REED. [L. S.]
